METAL DRAWING DIE

Frohman Anderson, Brooklyn, N. Y., assignor of
two-fifths to Ida Karl Adler, New York, N. Y.

Application February 8, 1940, Serial No. 317,830

4 Claims. (Cl. 153—32)

This invention relates to metal working and more particularly to dies for forming curved sheets of metal from flat sheet stock, as required in the manufacture of automobile and airplane bodies, boats or other fabricated articles.

Heretofore these curved sheets have been formed by die stamping or rolling machines which are of high initial cost due to the accurate machining required of their component parts, which are necessarily heavy, cumbersome, large, and the dies are adapted to make but a single shape. Also, there are many shapes desired in fabricated articles that do not lend themselves readily to die stamping and rolling from flat sheets, due to the metal required at different zones to maintain a generally uniform thickness and strength and without wrinkles. Furthermore, formation of shapes by die stamping is limited by the practical size of the punch presses. The production costs of sheets made by such machines have been high due to the extreme precision required in their operation and the high cost of replacement of the dies and the rolls themselves, should they become marred and produce surface scratches, which are undesirable especially in airplane bodies where skin resistance and corrosion is so greatly to be avoided.

In both the die stamping and rolling processes, flash or wastage is involved in every operation as metal must be available outside the desired shape for holding the sheet in the die press or at the edges of rolls. This flash must be removed by a further process of stamping or trimming.

The principal object of this invention is to provide a simple machine for forming a flat sheet of metal into a curved shape having predetermined transverse or longitudinal curvature or both.

Another object of the invention is to provide a simple die drawing unit which can be adjusted during the drawing of a sheet to vary the curvature of the sheet throughout its length.

Another object of the invention is to provide a die drawing unit by means of which curved sheets of metal may be duplicated even though each drawn sheet may have varying curved surfaces at different zones along its length.

Another object of the invention is to provide a die drawing unit that automatically produces through the length of the draw sheet, surfaces of varying curvatures.

Another object of the invention is to provide a simple die drawing machine adapted to form sheets of varying curvature from sheet blanks

cut to the configuration of the finally formed shape.

Another object of the invention is to provide a simple die drawing machine adapted to form 5 sheets of varying curvature from sheet blanks without requiring trimming after the forming operation.

Another object of the invention is to provide a simple die drawing machine adapted to form 10 sheets of varying curvature from sheet blanks without maintaining a transverse tension in the sheet as it passes through the die unit.

Further objects of the invention will be apparent from the specification and drawings forming 15 a part of the application.

The dies of one of my drawing units are characterized by at least one of the dies having a working edge of varying shape and sharpness throughout its length as it is mounted trans- 20 versely in the unit, over which the drawn sheet is bent and worked as it passes over the die. The drawing of the sheet over this edge causes it to become elongated in varying amounts 25 throughout its thickness depending upon the degree of sharpness of the bend, which in turn is dependent upon the shape and sharpness of the working edge of the individual die and its relative position from a second rigid surface, whether the latter be the working edge of another die or 30 a straight edge of a guiding surface. The elongation of the sheet as it is drawn over the working edge of a die is greater at the relatively sharper points of the working edge and is caused by the adjustment of metal to its deformation 35 as it passes over the working edge and, if the metal is stretched beyond its elastic limit, the sheet is given a permanently formed shape. At the same time the sheet is stretched and worked 40 as it progressively passes between the working edges of the dies. In this manner an initially flat sheet is formed into one having a curvature.

In their more general aspects, die units embodying my invention include two dies with their working edges held in different planes and forming 45 with guide block two throats through which the sheet passes over the working edges of the dies where the sheet is bent, stretched and worked into a desired curved shape. The second throat through which the sheet passes is so 50 shaped that the distances between corresponding points on the two cooperating dies vary throughout the transverse lengths of the throats. These unequal distances cause unequal longitudinal stretching of the longitudinal portions of the 55 sheet as it progressively passes between the

throats, the greater the distance between corresponding points of the two dies, the greater the stretching. This stretching and working of the sheet is in addition to that resulting from the bending and working of sheet on the working edges of the throats. Either or both of the die throats may be curved to obtain predetermined forms of the drawn sheet.

The working edges of my dies are in general relatively sharp, at least throughout a portion of their lengths. The sharpness depends in general upon the degree of stretching desired by a particular section of the working edge of the die. The degree of sharpness of the working edge is also generally dependent upon the gauge and the physical characteristics of the material being drawn, the working edge being sharper for thinner gauges.

My invention also includes the feature of positioning the working edges of the dies relative to each other and changing the relative positions of the working edges during the drawing and thus form a sheet into a shape having varying degrees of curvature throughout its length.

In forming a die throat of one embodiment of my invention, a guide block is provided whose working surface is substantially parallel to the working edge of the die, and extending back from that edge a distance sufficient to substantially keep the sheet in contact with the surface of die as it approaches and reaches the working edge. This block is necessary to overcome the tendency of the sheet to maintain its own plane when it is bent over the working edge of the die. It also prevents bulging of the sheet due to the difference in tension of the different longitudinal portions of the sheet as it is stretched unequally in those longitudinal portions. This unequal longitudinal stretching would manifest itself by creating other bulges behind the bulges caused by the sharp bending at the working edge of the die, which latter bulges would occur relatively near the working edge.

In the prior art, rolling machines have been disclosed showing changes in direction of a sheet as it passes through one or more pairs of rolls, wherein the gap between the rolls forms merely a line contact with the sheet and at which line the force of the rolls is exerted in equal amounts on both sides of the sheet. In my invention there is no such pressure placed on the sheet as it passes over the working edge of the die. The sheet of my invention develops a pressure against the working edge due to the resistance to bending of the sheet. In my invention there is a component of this pressure parallel to the working surface of the die, which provides the retarding force necessary for establishing tension in that portion of the sheet between two cooperating throats, which rolling machines do not have.

Furthermore, it is obvious that since the rotating rolls of the prior art are in contact through the sheet on only a very limited area, which approaches a line, unusually high pressures are required to exert any retarding force to a sheet being pulled through a pair of rolls. Also, this force is critical as the volume of the metal between the rolls is small and too much pressure extrudes the metal and too little pressure results in slippage at the transverse center of the rolls where the tension on the sheet is greatest, thus causing wrinkles to form behind the rolls. Also, it is well known that sheets received from rolling mills vary in thickness and such variations would naturally cause variations in the pressures

of the rolls on the sheet, as the rolls are set rigidly in definite positions.

It is also well known in the rolling art that flanges must be turned up at each side of the sheet throughout its entire length, to engage holding surfaces at the sides of the rolls to prevent transverse slippage of the sheet during the rolling. It is apparent that the use of my drawing dies eliminates the operation of forming flanges on the sheets before passing them through a rolling machine and trimming the sheets after the rolling, as well as eliminates the cost of the scrapped material. Sheets may be drawn through my die units that are narrower than the width of the dies. The character of my invention is drawing and not rolling.

The throats in my die units may be staggered in parallel horizontal, vertical or transverse planes, so that the sheet is bent at an angle at the edge of the first die throat and then bent again as it passes through the second die throat. That portion of the sheet which at any instant is between the throats is under tension, causing the sheet to be stretched and worked. This stretching and working contributes to the final shape of the sheet.

In the case of a single die throat, the angle of approach of the sheet to the working edge may be adjusted to produce varied effects in the drawn sheet by providing a guide block adjustable in its position relative to the working edge. When using only one throat, it is preferable at times to make the portion of a guide block near the throat of a form generally complementary to the working edge of the die.

For sheet metal of medium or heavy gauge, or of high tensile strength, the working edges of the dies may be made of hard metal. However, the working faces may be made of such materials as a hard wood or fiber, for shaping sheets of low tensile strength. In all cases, the working edges of the dies should be smooth so as to exert an ironing effect on the sheets and without scratching or otherwise marring the drawn surfaces. However, should rough surfaces corrugated or otherwise irregular shapes be desired, the working edges may be made up of irregular curves or of curves and straight lines.

With dies of the type generally described herein, it is possible to form sheets with longitudinal curvatures such that the sheets will tend to form comparatively tight spirals after passing through the unit. In this condition, sheets having compound curvatures imparted to them may be coiled and shipped or handled in a small container. When unpacked and uncoiled, they will assume the desired form.

Such metals as aluminum, magnesium, Monel and stainless steel have been handled successfully with drawing dies of my type without the drawn sheets being cracked, torn, wrinkled or otherwise damaged.

Reference is had to the accompanying drawings forming a part of this specification, in which:

Fig. 1 is a top plan view, partly broken away, of a typical form of a single die throat type of drawing unit embodying the invention;

Fig. 2 is a view in section taken on line 2—2 of Fig. 1;

Fig. 3 is an enlarged view in perspective of the male die used in arrangement shown in Figs. 1 and 2;

Fig. 4 is an enlarged view in perspective of the

female die used in the arrangement shown in Figs. 1 and 2;

Fig. 5 is an enlarged view in perspective of a metal sheet as it assumes a form in passing through the die unit shown in Figs. 1 and 2;

Fig. 6 is a top plan view, partly broken away of a typical form of a two throat drawing unit embodying the invention;

Fig. 7 is a view in section taken on line 7-7 of Fig. 6;

Fig. 8 is a view in section taken on line 8-8 of Fig. 6;

Fig. 9 is a view in section taken on line 8-8 of Fig. 6 but in position of maximum gap between throats and with the machine in position for loading the sheet;

Fig. 10 is a view in section similar to Fig. 8 but showing a vertically adjustable auxiliary creasing edge;

Fig. 11 is an enlarged view in perspective of a metal sheet showing its form at the bends as it passes through the drawing dies of Figs. 6-7 and 8;

Fig. 12 is a view in side elevation of a typical form of device embodying the invention, for imparting compound curvatures to sheets of metal;

Fig. 13 is a view in perspective of a metal sheet showing its form and its two bends as it passes through a pair of drawing dies, to produce greater elongations at the sides of the sheet than in its center;

Fig. 14 is a view in perspective of a metal sheet having a curvature given it as it passes through a die throat having a curved working edge and through a second die throat having a different curved working edge;

Fig. 15 is a view in perspective of a metal sheet showing its form at its four bends as it passes through four throats, the first two being similar to those in Fig. 11 and the last two being similar to those of Fig. 14;

Fig. 16 is a view in perspective of a metal sheet showing its form at its four bends as it passes through four throats, the working edges of which are similar to the form shown in Fig. 3;

Fig. 17 is an isometric sectional view of a four throat die unit taken on its central longitudinal plane to form the sheet shown diagrammatically in Fig. 15;

Fig. 18 is an isometric view showing the holding construction of the slides shown in Fig. 17; and

Fig. 19 is an isometric view of the actuating mechanism of the slides, the view being partially broken away to show the position of the sheet being drawn when the slides are somewhat extended from each other.

Dies embodying the invention may be used with any desired type of mechanism capable of drawing a sheet of metal through the die throats. As shown in Fig. 12, one form of drawing mechanism may suitably consist of a frame 1, along which moves table 2 having grooved sliding surfaces 3. The table 2 is provided with a rack 4, with which meshes a system of reduction gears 5 driven by an electric motor 6, whereby upon operation of the motor the table 2 travels along the frame 1. At the right hand end of the table 2, as viewed in Fig. 12, there is provided a standard 7, with a clamping head 8 having at the inner end of groove 9 a pair of jaws 10 for gripping the end of a sheet of metal 11. Standard 7 also has means for mounting one end of a replaceable cam unit or plate 12, to be described later. The sheet of metal is drawn by means of jaws 10 through a die

unit 13 mounted on a bed plate 1a secured to uprights 1b which are secured to or may be a part of frame 1. Uprights 1b support at their upper extremities a head unit 1c which houses a conventional actuating mechanism for toggles 1d. Toggles 1d adjust the position of ram 42 to which the upper part of die 13 is attached. The lower part of die 13 is attached to bed 1a.

Referring particularly to Figs. 1 and 2, a typical form of a single die throat may consist of a base plate 14 having at two corners thereof guide pin bosses 15 for guide pins 16. Spaced from base plate 14 but guided by guide pins 16 is top plate 17 which, together with the base plate 14 defines a cavity 18, in which are located elements defining a gap or throat 19. The die throat 19 is defined by a male die 20 and female die 21. On die 20 is formed the working surface or edge over which the sheet 11 is bent and stretched. Die 20 is dependent from top plate 17 and the vertical gap 22 of the throat is controlled by shimmed stop blocks 23.

Die 21 is mounted on slide element 24 which is 25 slideable along the base plate 14, in order to vary the character of the bend at throat 19. When the die is in operation, the horizontal thrust is received by heel plates 25 mounted on the inner side of guide pin bosses 15. Plates 25 engage the vertical finished surfaces 26 of top plate 17.

The slide 24, as previously indicated, is shiftable toward and away from die 20 shown in this instance as being shiftable in a horizontal plane. Slide 24 is guided at its sides by gibs 27 mounted on plate 14. The purpose of changing the position of the die 21 is to vary the angular approach of the sheet against the edge 28 of die 20. Thus, when the slide 24 moves die 21 closely adjacent to die 20, as shown in Fig. 2, so that an acute bend is made in sheet 11, a greater amount of stretch is imparted to the sheet 11 for the reason that the different layers of the sheet throughout its thickness are caused to stretch beyond their elastic limit in greater amounts than would be the case were die 21 further away from die 20.

Fig. 3 shows an enlarged view in perspective of the die 20. The working edge 28 varies in sharpness from its longitudinal center as it is mounted transversely in the unit, until at the ends of the die the edges become curved surfaces 29 of relatively large radii. In other words the working edge is rounded to a variable radius along its length, in the case shown there being virtually zero radius at the center and the radius increasing progressively from the center oppositely to each end where there is substantial radius. It will be apparent that a greater elongation will be imparted to the sheet at the point of greatest sharpness of die, for the drag imposed upon the sheet will be a function of the radius of curvature of the edge. The shifting of the die 21 toward and away from die 20 during the operation of the machine, as for example to the dotted line position 30 in Fig. 2, will vary the curvature imparted on the sheet 11 along its length.

In order to control the movement and position of the slide 24, a toggle link construction has been provided, as best shown in Figs. 1 and 2. The toggle construction consists of a pair of pivotally connected links 31 and 32, having their opposite ends pivotally connected to the slide 24 and to a rearward extension 33 on the base plate 14, respectively. At the opposite ends of slide 24, a similar toggle construction 34 and 35 is arranged except that link 35, pivotally connected to extension 36 of base plate 14, has a handle

extension 37 for imparting angular movement to the toggles. A cross link 38 connects the pivotally connected ends of links 34 and 35 to the pivotally connected ends of links 31 and 32. Thus by operating handle 37, the links may be moved from an in-line position, as shown in Fig. 1, into angular relation, thereby retracting the slide 24. As stated before, the effect of moving the slide 24 is to vary the curvature of the drawn sheet. Other means for moving slide 24 will be described hereinafter in relation to Figs. 6 to 9 inclusive.

As shown in Figs. 6 to 9 inclusive, a typical form of a two die throat machine may consist of a base plate 14 which is mounted on a bed 1a, as shown in Fig. 12. Spaced from the base plate 14 but connected rigidly thereto by means of guide pins 16, heel plates 25 and stop blocks 23, is a top plate 17, which, together with the base plate 14 define a cavity 18, in which are located dies defining a pair of die throats 40 and 41. Top plate 17 is fixed to ram 42 of draw bench (see Fig. 12). The die throat 40 is defined by a slide element 43 of generally rectangular cross-sectional shape, which is slideable along the base plate and a superimposed pressure plate 44, which is supported by the top plate 17. As illustrated in Figs. 6 to 10 inclusive, the slide 43 and plate 44 may be reduced in weight by making them hollow. The plate 44 is supported on the top plate 17 by means of a plurality of retainer screws 45, which are provided with reduced threaded ends 46 and enlarged heads 47. The threaded ends 46 are screwed into the plate 44 and the heads 47 retain it against separation from the top plate 17, while allowing relative movement therebetween. The pressure plate 44 is normally forced downwardly into spaced engagement with the slide 43, by means of springs 48 disposed in holes 49 in the top plate 17. Top plate 17 when raised, brings with it die 51 and permits the sheet 11 to be threaded through or loaded in the die unit. The raising of die 51 permits the sheet to extend between slide 43 and plate 44 and beyond the die unit, where it can be gripped by jaws 10. (See Fig. 9.) The springs 48 together with the weight of the plate 44, assure that the sheet 11 will remain flat when top plate 17 and die 51 are lowered and die 51 and block 53 form throat 41. A proper spacing of throat 40 is made by adjusting the height of stop blocks 23 by shims.

At the left hand edge of the slide 43, as viewed in Figs. 8 to 10 inclusive, die 50, which may be made of hardened metal or wood or fiber, forms a working surface and a working edge over which the sheet of metal 11 is bent. As shown in Fig. 7 the die throat 40 is straight from end to end and therefore the sheet of metal is only bent at an angle relative to the throat 40. While die throat 40 is illustrated as being straight, it will be understood that it may be of irregular shape according to the results desired, as illustrated in Figs. 14 and 16. To resist excessive wear plate 44 is provided with an interchangeable insert 50a.

The die throat 41 is defined by die 51 in the lower right hand edge of a flange 52 which depends from and is a part of the top plate 17. The lower face of the die 51 is formed on a curve which extends from end to end, as shown in Fig. 7. While the die 51 is illustrated as being a smooth, continuous curvature, it will be understood that it can be an irregularly curved die, if it is desired to impart an irregular or isometric curvature to the sheet of metal, inasmuch as the curvature of this edge determines the degree of

elongation at different stations on the width of the sheets in conjunction with the particular die throat 40 as described. The die throat 41 may take the form of a curve with outer edges below the mid point, which would deform the sheet as illustrated in Fig. 13.

Cooperating with the die 51, in defining the die throat 41, is a block 53 which is fixed to the base plate 14 and retained in position by means of a rail 54 extending across the plate 14. The block 53 has its upper edge curved substantially complementarily to the curvature of the die 51, and thus defines the transversely curved die throat 41.

15 The slide 43, as previously indicated, is shiftable toward and away from the die throat 41, as shown in this particular instance, in a horizontal plane. The purpose of changing the position of the die throat is to vary the amount of curvature 20 to be imparted to the sheet 11 throughout its length. Thus, when the die throat 40 terminates closely adjacent to the die throat 41, as disclosed in Fig. 8, so that an abrupt bend is made in the sheet 11, the greatest longitudinal curvature may 25 be imparted to the sheet 11 as will be apparent from consideration of Fig. 11.

Fig. 11 represents sheet 11 marked with longitudinally and transverse parallel lines. Line YWY represents the die throat 41. Line YYV 30 represents the die throat 40 when slide 43 is close to die throat 41 as in Fig. 8. Dotted line ZUZ represents the position of the die throat 40 when it is removed away from die throat 41 as in Fig. 10. Assuming that the distance XY and TW are 35 equal, we have: The ratio UWT/ZYX is greater than 1 but approaches 1 when YZ becomes infinite, so that the further away the die throat 40 is removed from die throat 41 the less stretch the sheet will be subjected to along its center. 40 Also, it will be seen, the ratio UWT/ZYX becomes a maximum when YZ becomes 0, when the maximum stretch is obtained. The second effect that produces elongation is that of the angular approach at the working edges of the throats. 45 Again, looking at Fig. 11 it may be seen that the sheet would be given less elongation when moving along path UWT than when moving along path UVWT. It may also be observed that the path ZYX would have no angular deflections and 50 therefore no elongation. Thus it will be apparent that by shifting the slide 43 toward and away from the dies 51 and block 53 during operation of the machine, the curvature imparted to the sheet 11 throughout its length may be varied as 55 may be desired.

In order to control the movement and position of the slide 43, a toggle link construction has been provided, as best shown in Fig. 6. The toggle construction is similar to that described in 60 Fig. 1 but with certain modifications. Link 35 instead of having a handle extension, as in the previous case, has a bevel gear extension 55 which meshes with a bevel pinion 56 which is fixed to the end of a shaft 57 journaled in standard 65 58 mounted on extension 36 of the base plate 14. The shaft 57 is rotated by the crank 59 whereby the links 31, 32 and 34, 35 may be moved from in-line position, as shown in Fig. 6, into angular relation, thereby retracting the slide 43. Thus, by 70 rotating the crank 59, it is possible to advance and retract the slide 43 to vary the spacing of the working faces of the die throats 40 and 41 and thereby vary the curvature of the sheets. While a lever, crank and gear drive have been illustrated for shifting slide 43, it will be understood

that any other desired actuating mechanism may be used, such as a cam plate 12 which is provided with slot 60 of predetermined shape for regulating the movement of the slide during the passage of a sheet through the drawing die. Slot face 61 of cam groove 60 engages cam follower 62 which is connected to cross link 38. It is apparent that with the same cam plate in position, the curvatures applied to sheet 11 may be duplicated.

In drawing the sheet over a working edge of the die, there is unequal elongation of the sheet throughout its thickness, and there is created a tendency for the sheet to curl up in a spiral. If the worked sheet passes over a second working edge in a bend in an opposite direction, this tendency to curl may be lessened or eliminated according to the degree of bend at the second working edge. Where there has been unequal bending at a plurality of working edges and it is desired to eliminate the over-all tendency for the sheet to curl, there is provided, as shown in Fig. 10, a sharp edged block 63, of the general form of block 53, positioned to exert a pressure on the sheet after it has passed through the last die throat. Block 63 is held in position by rail 64 and may be adjusted in position by shims 65. Thus by drawing the sheet over block 63, the tendency of the sheet to curl may be eliminated.

This final working edge provided by the block 63 thus functions to determine the amount of longitudinal curvature left in the drawn sheet under condition of equilibrium. The transverse curvature imparted by a given set of dies depends upon the longitudinal curvature, the transverse curvature varying inversely with the longitudinal curvature. The block 63 will therefore be so adjusted that it will leave just the right amount of inherent longitudinal curvature. This will in all normal circumstances be considerably less than a coiled up or spiral condition, such as would result upon release of the sheet if the unbalance in inherent stresses produced at the last drawing die were not in part at least overcome.

In operation, the table 2 is moved to its left-hand position (see Fig. 12) and top plate 17 and the parts attached thereto are raised by vertically moving the ram 42 to the position shown in Fig. 9. Pressure plate 44 is now separated from slide 43 sufficiently to permit the sheet 11 to pass therebetween and beyond die 51, which is also in its raised position, and to the jaws 10, where it is clamped. Ram 42 is then lowered until plate 17 rests on pressure plate 44. This movement also lowers die 51 and in its lower position forms throat 41 with the sheet 11 in position for drawing. The motor 6 is then started and the table 2 travels along the frame 1, in the direction of the arrow, pulling the sheet through the die unit. As the sheet passes through the die unit, it is bent over the working edges of the dies as described. While the sheet is moving through the die unit, the horizontal spacing between the die throats 40 and 41 may be varied by rotating the crank 59, or by the action of cam slot 60, thereby varying the radius of curvature of the sheet to cause it to be curved in a predetermined way.

My arrangement is adapted to draw a large variety of curved sheets from one set of die throats and with other sets of die throats of other characteristics, a few of which have been described, an extremely large number of shapes may be obtained from a single die unit. Thus, for example, if it is desired to curve a sheet longitudinally in the same direction and transversely in the direc-

tion opposite to the curvatures disclosed in Figs. 7 and 8, the die 51 and block 53 can be replaced by another set having upwardly curved, rather than downwardly curved, complementary edges, the working edge of which is indicated in Fig. 13 by the line b, so that the center of the sheet is substantially in alignment with the die throat 40, the working edge of which is indicated in Fig. 13 by the line a, and the ends of the throat 41 are disposed below the die throat 40. With this type of construction, the edges of the sheet will be stretched to a greater extent than the center portion, and thus a concavely curved sheet will be produced, as shown in Fig. 13.

Likewise, the working edges of both of the die throats may be downwardly curved, as indicated by lines a and b in Fig. 14. Four die throats may also be used, the working edge of one of which may be straight and the others may be curved, as shown by lines a, b, c and d in Fig. 15, or as shown by lines a, b, c and d in Fig. 16.

Referring particularly to Figs. 17, 18 and 19, the sheet 11 is shown passing between slides 43 and 43a, which are constrained to move together by guide pins 16. The two slides are kept separated by shimmed stop blocks 23. One edge of die 50 and insert 50a form the first die throat 40. Die throat 41 is formed by one edge of die 51 and the flat surface insert 53. Die throat 41a is formed by another portion of the edge of die 51 and the working edge of insert 53. Die throat 41b is formed by die 51a and the insert 53a.

Slides 43 and 43a move between slides 66 and 67, which in turn move between upper plate 17 and lower plate 15. Upper slide 67 is guided at its sides by gib blocks 68, which have flanges 69 to engage with flanges 70 of upper slide 67 when upper plate 17 is raised to position sheet 11 preparatory to drawing. Slides 66 and 67 and die plates 15 and 17 are also provided with stop blocks (not shown) similar to blocks 23.

The slides are moved relative to each other and to the stationary throat 41b by a double link system consisting of links 31 and 34 and links 71 and 72, which actuate slides 43 and 43a. Links 71 and 72 have also pivots 73 and 74 mounted at their longitudinal center and connected to links 75 and 76, which are pivotally connected to slides 66 and 67. Motion is transmitted from cam follower 62, moving in cam groove 60 in cam 12 by means of tie rods 38 connected to pivots 73 and 74.

It is apparent that the die throats may be moved during the drawing of a sheet through the unit either in a direction parallel, transversely or vertically to the direction of the draw, or any combination of them.

Inasmuch as only the dies need be replaced, it will be evident that the expense of adapting the machine to any type of work is extremely small while its versatility by reason of the ready replacement of the dies is correspondingly great.

While the invention has been disclosed as applying to the drawing of metal sheets, it will be understood that it applies to sheets of other materials, such as fiber sheets, that are adapted to drawing and working processes.

In view of the many variations to which these dies are susceptible, the specific embodiment of the die described above should be considered as illustrative and not as limiting the scope of the following claims.

I claim:

1. Apparatus for shaping sheet metal comprising, in combination with means for pulling

the sheet edgewise, a die member having a working edge and an opposing member cooperating with the die member to form a die throat through which the sheet is pulled, and guide means for the sheet in advance of the die member positioned to direct the sheet to the throat at an angle to its direction of pull through the throat, the working edge of the die member being variably rounded along its length so as to effect a differential drag upon the sheet.

2. Apparatus for shaping sheet metal comprising, in combination with means for pulling the sheet edgewise, a die member having a working edge and an opposing member cooperating with the die member to form a die throat through which the sheet is pulled, guide means for the sheet in advance of the die member positioned to direct the sheet to the throat at an angle to its direction of pull through the throat, the working edge of the die member being variably rounded along its length so as to effect a differential drag upon the sheet, the guide means being adjustable toward and away from the transverse plane including the die throat, and means to effect said adjustment.

3. Apparatus for shaping sheet metal comprising, in combination with means for pulling the sheet edgewise, a die member having a work-

ing edge that is variably rounded along its length and an opposing member of complementary shape cooperating with the die member to form a throat through which the sheet is pulled, and guide means for the sheet in advance of the die member transversely offset from the throat on the side including the die member so as to direct the sheet to the throat at an angle to its direction of pull through the throat and thereby cause it to be drawn over the working edge.

4. Apparatus for shaping sheet metal comprising, in combination with means for pulling the sheet edgewise, a die member having a working edge that is variably rounded along its length and an opposing member of complementary shape cooperating with the die member to form a throat through which the sheet is pulled, guide means for the sheet in advance of the die member transversely offset from the throat on the side including the die member so as to direct the sheet to the throat at an angle to its direction of pull through the throat and thereby cause it to be drawn over the working edge, the guide means being adjustable toward and away from the transverse plane including the die throat, and means to effect said adjustment.

FROHMAN ANDERSON.

Certificate of Correction

Patent No. 2,395,651.

February 26, 1946.

FROHMAN ANDERSON

It is hereby certified that the above numbered patent was erroneously issued to the inventor, said "Anderson assignor of two-fifths to Ida Karl Adler, of New York, N. Y.," whereas said patent should have been issued to the inventor, as sole owner thereof; and that the said Letters Patent should be read with this correction therein that the same may conform to the record of the case in the Patent Office.

Signed and sealed this 17th day of December, A. D. 1946.
